LE GRAND PARISH.
LOCOMOTIVE FIRE BOX CONSTRUCTION.
APPLICATION FILED MAY 15, 1914.

1,156,368.

Patented Oct. 12, 1915.

UNITED STATES PATENT OFFICE.

LE GRAND PARISH, OF NEW YORK, N. Y.

LOCOMOTIVE-FIRE-BOX CONSTRUCTION.

1,156,368.

Specification of Letters Patent. Patented Oct. 12, 1915.

Application filed May 15, 1914. Serial No. 838,654.

To all whom it may concern:

Be it known that I, LE GRAND PARISH, a citizen of the United States, residing at New York city, in the county of New York and State of New York, have invented certain new and useful Improvements in Locomotive-Fire-Box Construction, of which the following is a specification.

This invention relates to locomotive fire-box constructions and has particular reference to an improved arrangement of refractory arch or baffle wall on the circulation tubes whereby more perfect combustion is obtained in the fire-box with a consequent increase in efficiency. In conjunction with the foregoing, my invention also contemplates the provision of an economical and efficient fire-box construction whereby increased circulation between the water spaces is obtained and at the same time the circulation tubes receive the beneficial protective action of the bricks constituting the refractory arch where the fire is hottest. By this invention I obtain greater efficiency effects and better gas mixing results than by previous methods without the use of any more bricks or brick material than in previous arches.

The foregoing, together with such other objects as may hereinafter appear or are incident to my invention, I attain by means of a construction, the preferred embodiment of which I have illustrated in the accompanying drawings, wherein—

Figure 1 is a longitudinal section through a locomotive fire-box of standard construction showing my invention applied thereto; Fig. 2 is a transverse section through the refractory arch taken on the line II—II of Fig. 1 but drawn on a larger scale; Figs. 3, 4 and 5 are similar sections through modified types of the improvement.

Referring to the general construction of the fire-box, the inner fire-box comprises the tube-sheet 1, the side sheet 2, the back sheet 3, and the crown sheet 4. The outside fire-box comprises a throat sheet 1^a, the outer side sheets 2^a (not shown), the back sheet 3^a, and the tube or cover sheet 4^a. The water legs or spaces are closed by the usual mud ring 5; the back sheets 3 and 3^a are connected by the stay-bolts 6; and the crown sheet and cover sheet are connected by the radial stay bolts 7. At the forward end of the fire-box the tube sheet 1 is carried up-

ward to provide the usual flue sheet 13 in which the ends of the flues 12 are expanded.

In order to carry out my invention, I depart from the usual practice and provide a plurality of arch-supporting members which preferably are circulation tubes extending rearwardly and upwardly from the front water space to the rear water space, said tubes being preferably arranged in two rows 8 and 8^a, the one above the other, although they may be arranged differently and still serve the purposes of my invention. In the construction of Figs. 1 and 2, the refractory arch comprises a plurality of rows of bricks arranged on the tubes in approximately a staggered relation. In placing the bricks I prefer to arrange the openings in staggered relation; that is, so that the upper bricks come over openings below so as to get as much deflection of the flame as possible. The bricks of the central row 9 are socketed or otherwise supported on the central tubes of the lower row 8^a; the proximate rows of bricks 10 and 11 are supported at their inner ends on the corresponding central tubes of the upper row 8, and at their outer ends on the outermost tubes of the upper row 8; and the rows of tubes 14 and 15 which comprise the side walls of the arch are supported at their inner ends on the outermost tubes of the lower row 8^a and incline upwardly, their outer ends bearing against the side sheets 2.

The construction shown in Fig. 3, in effect, constitutes a reversal of the construction of Fig. 2, the central row of bricks 9 being supported on the central tubes of the upper row, the rows of bricks 10 and 11 being supported on the tubes of the lower row, and the end or side rows of bricks 14 and 15 being supported on the outermost tubes of the upper row and bearing against the side sheets in the manner already described.

In Fig. 4 I have shown a construction in which the rows of bricks 9, 10, and 11, which constitute the central portion of the arch, are supported at one end on the lower row of tubes and at the other end on the upper row of tubes. In this construction, however, the row of bricks 14 are supported at one end on a side tube of the lower row and bear at the other end against the side sheet, while the row of bricks 15 is supported in a similar manner on a side tube of the upper row.

In the construction shown in Fig. 5, the bricks of the row 9 are socketed on the cen-

tral tubes of the lower row 8^a, and the bricks of the rows 14 and 15 are socketed and supported in the same manner as the corresponding bricks in the construction of Fig. 4. The bricks of the rows 10 and 11, however, are disposed at an angle, being supported at one end on the central tubes of the upper row of tubes 8 and at the opposite ends on the outer tubes of the lower row of tubes 8^a.

It will be seen from the foregoing that in each type of refractory arch shown, the bricks or rows of bricks are supported on the tubes in such manner as to present an interrupted surface to the gases and products of combustion, with circulation spaces or intervals between the bricks, which deflects the gases in different directions and secures an intimate admixture thereof, all of which results in a more complete combustion of the gases, which of course increases the efficiency of the fire-box. It will be noted that in conjunction with this advantage, I also obtain an increased circulation between the water walls by virtue of the provision of the additional circulation tubes which are provided in order to obtain the improved arrangement of the arch bricks which I have described. At the same time it will be observed that all of the tubes are protected by the bricks of the arch. The life of the tubes is thus prolonged. It will be apparent that while the gases are deflected and thoroughly inter-mixed, their course of travel is sufficiently altered to obtain more complete combustion and better ignition, which is one of the principal objects of this invention.

I claim:

1. In combination, a locomotive fire box having water walls and a flue sheet, a plurality of flues extending through the flue sheet and forwardly thereof, two rows of circulation tubes inclining rearwardly and upwardly from a point below the flues and connecting the front and rear water walls of the box, one of said rows being located above the other and spaced apart to permit the introduction of locomotive fire box arch bricks between the rows, and an arch supported on the circulation tubes extending

from a point adjacent the front water wall of the fire box rearwardly a portion of the distance to the rear water wall, said arch comprising a plurality of removable refractory arch bricks arranged in rows, the wing rows of bricks being supported on the end members of the rows of circulation tubes and on the side sheets, and the central rows of bricks being supported on circulation tubes extending in different planes so as to provide spaces between the rows, whereby the bricks are subjected to the cooling action of the tubes and the gases of combustion are thoroughly mixed, while the ends of the flues are protected. 55

2. In combination, a locomotive fire box having water walls and a flue sheet, a plurality of flues extending through the flue sheet and forwardly thereof, two rows of circulation tubes connecting the front and rear water walls of the fire box and extending rearwardly and upwardly from the front wall at a point beneath the flues, the tubes of one row being located substantially 70 vertically above the tubes of the other row and the two rows being spaced apart to permit the introduction of arch bricks therebetween, and an arch supported on the circulation tubes extending from a point adjacent the front water wall of the fire box rearwardly a portion of the distance to the rear water wall to protect the ends of the flues, said arch comprising a plurality of removable refractory arch bricks arranged in rows, the wing rows of bricks being supported on one of the end members of the rows of circulation tubes and on the side sheet, and the central rows of bricks being arranged on circulation tubes extending in 75 different planes so as to provide lateral gaps between the rows, whereby the bricks are subjected to the cooling action of the tubes and the gases of combustion are thoroughly mixed. 80

In testimony whereof I have hereunto signed my name in the presence of the two subscribed witnesses.

LE GRAND PARISH,
Witnesses:

PAUL SYNNESTVEDT,
HARVEY L. LECHNER.
